Byrnes, Gibbons, Pamela

UNITED STATES PATENT OFFICE.

GREGORY D. MANTLE, OF PITTSBURGH, PENNSYLVANIA, ASSIGNOR TO MANTLE ENGINEERING COMPANY, OF PITTSBURGH, PENNSYLVANIA, A CORPORATION OF PENNSYLVANIA.

GLASS FURNACE.

Application filed October 8, 1926. Serial No. 140,269.

This invention is for an improvement in glass furnaces, and more especially the smaller types of continuous furnaces adapted for special small batches of glass and intended primarily to replace day tanks now commonly used.

In continuous furnaces of the type referred to, the furnace is divided intermediate its length by a bridge wall so as to form a melting chamber and a working chamber. Heat is provided by burners located at the charging end of the melting chamber and a flue to recuperators is provided at the top of the furnace at the working end of the chamber through which the products of combustion are removed.

Considerable difficulty has been encountered in the use of these tanks, the circulation of all of the products of combustion coming directly over the glass in the working end of the chamber, and to this end my invention proposes to provide for the protection of the working chamber while maintaining proper working temperatures therein.

The nature of the invention may be readily understood by reference to the accompanying drawings, which illustrate one embodiment of my invention, and in which:

Figure 1 represents a longitudinal vertical section through a furnace embodying my invention.

Figure 2 represents a transverse section in the plane of line II—II of Figure 1.

In the drawings, 2 designates the interior of a small furnace of the continuous type having a bottom 3, side walls 4, a top 5 which is preferably arched, a front or working end wall 6, and a rear or charging end wall 7. A charging opening of the usual type is provided in or adjacent the rear wall 7.

The interior of the furnace is divided intermediate its ends, and preferably at a point slightly past the middle toward its front wall 6, by a bridge wall 8 of less height than the interior of the furnace so that a gas circulating passage exists above this wall. Throats 9 are provided in the bridge wall adjacent the bottom.

The function of the bridge wall is to divide the interior of the furnace chamber below the desired level into a melting chamber 10 where the raw materials are melted as they flow toward the bridge wall and a

working chamber 11 into which the fined glass flows from the melting chamber through the throats 9, and from which it is withdrawn.

A working door 12 is provided in the front wall 6 of the furnace, similar doors 12^a being shown in the side walls, and it is through these doors that the glass is removed. One or more burners are provided in the rear wall 7, the holes for the burners being designated 14. The products of combustion are removed from the interior of the furnace through a flue or stack opening 15 at the working end of the furnace. These gases, in usual practice, are delivered to a recuperator at this point.

In order to protect the glass in the working chamber 11, I propose, according to the present invention, to provide a closed refractory arch 16 over the working chamber and extending from the bridge wall to the forward or working end wall 6 of the furnace. This arch, in effect, provides a muffle or circulating passage outside the working chamber by means of which a high temperature can be maintained in the working chamber without directly subjecting the glass in the chamber to the gases of combustion. This also prevents the gases of combustion from escaping through the working doors, and prevents interference with the circulation of the gases of combustion by reason of air entering the working doors.

If necessary, auxiliary burners can be provided for the working end of the chamber under the muffle wall or arch 16, ports for these burners being indicated at 17. These local or auxiliary burners provide flexibility of temperature control and adjustment of temperatures to meet local conditions while avoiding the necessity for the entire mass of the products of combustion from flowing over the glass in the working chamber as has heretofore been the practice.

The advantages of the present invention have already been indicated, these advantages arising from the provision of the arched muffle-tile wall 16 and the provision of the burner passages 17.

While I have illustrated and described one preferred embodiment of my invention, it will be understood that the invention may be otherwise embodied and that various changes and modifications may be made therein

within the contemplation of my invention and under the scope of the appended claims.

I claim:

1. A continuous glass furnace having a bridge wall therein dividing the furnace into a melting chamber and a working chamber, the upper part of the interior of the furnace being continuously open to the circulation of gases, a partition extending from the bridge wall horizontally over the working chamber, a flue in the furnace at the working end above the partition and a fuel burner at the melting end of the furnace.

2. A glass furnace of the continuous type having an elongated interior chamber, a bridge wall intermediate the ends of the chamber transversely thereof for separating the furnace into a melting end and a working end, the upper part of the chamber being continuously open to the circulation of gases therealong, a burner at the melting end of the furnace, an outlet flue at the working end of the furnace, and a horizontal partition extending from the bridge wall over the entire working end of the furnace.

3. A glass furnace of the continuous type having a melting chamber and a working chamber, a gas circulating passage about at least a portion of the working chamber, and means for effecting the circulation of gases of combustion longitudinally of the furnace from the melting end to the working end and along the said gas circulating passage.

4. A glass furnace of the continuous type having a melting chamber and a working chamber, a muffle above the working chamber, means for introducing fuel into the melting end of the furnace, and a flue at the working end with which the muffle communicates.

5. A glass furnace of the continuous type having a bridge wall in the lower portion thereof dividing the furnace into a melting chamber and a working chamber, the upper part of the interior of the furnace being continuously open, a partition extending horizontally over the working chamber, said partition being spaced below the top of the furnace, and an auxiliary burner opening in the walls of the furnace at the working end thereof and below the said horizontal partition.

6. A glass furnace of the continuous type having bottom, side, top and end walls, a bridge wall within the furnace transversely thereof, the top of the bridge wall being below the top wall of the furnace whereby the space above the bridge wall is open to

the circulation of gases through the furnace, a burner in one end wall of the furnace, a flue adjacent the other end wall of the furnace and a horizontal partition extending from the bridge wall to the end wall of the furnace adjacent the flue.

7. A glass furnace of the continuous type comprising an elongated furnace structure having the lower part of the interior thereof divided by a bridge wall into a working chamber and a melting chamber, an arch over the working chamber, and below the top of the furnace whereby a gas circulating passage is provided throughout the length of the furnace, a flue at one end of the furnace, said furnace having a burner opening at the other end thereof.

8. A glass furnace of the continuous type comprising an elongated furnace structure having the lower part of the interior thereof divided by a bridge wall into a working chamber and a melting chamber, an arch over the working chamber and below the top of the furnace whereby a gas circulating passage is provided throughout the length of the furnace, a flue at one end of the furnace, said furnace having a burner opening at the other end thereof, the furnace also having a burner opening in the working chamber thereof below the said arch, said working chamber having working doors therein.

9. A glass furnace of the continuous type having a melting chamber and a working chamber, said chambers being separated by a bridge wall of less height than the interior of the furnace whereby the upper portion of the furnace is continuously open to the passage of gases therethrough, said bridge wall extending from a point close to the bottom of the furnace to a point well above the normal glass level of the furnace, a partition extending horizontally over the working chamber, and a flue for inducing the flow of gases along the top of the partition.

10. A glass furnace of the continuous type having a melting chamber and a working chamber, said chambers being separated by a bridge wall of less height than the interior of the furnace whereby the upper portion of the furnace is continuously open to the passage of gases therethrough, and a partition extending horizontally over the working chamber, said working chamber being provided with auxiliary heating means.

In testimony whereof I have hereunto set my hand.

GREGORY D. MANTLE.
